Patented Feb. 14, 1922.

FIG. 1

FIG. 2

Inventor
Louis Cohen
by his attorney
Carl A. Richmond

UNITED STATES PATENT OFFICE.

LOUIS COHEN, OF WASHINGTON, DISTRICT OF COLUMBIA.

RADIO RECEIVING SYSTEM.

1,406,442.

Specification of Letters Patent. Patented Feb. 14, 1922.

Application filed December 28, 1918. Serial No. 268,720.

To all whom it may concern:

Be it known that I, LOUIS COHEN, a citizen of the United States, residing at Washington, in the District of Columbia, have invented a new and useful Improvement in a Radio Receiving System, of which the following is a specification.

The principal object of my invention is to provide new and improved apparatus for 10 radio telegraph receiving purposes. Another object of my invention is to provide an arrangement of radio receiving apparatus that shall be highly selective in response to waves of definite frequency. Still another 15 object of my invention is to connect a radio detector to a receiving antenna through a double coupling, electrostatic and electromagnetic, the latter being a comparatively tight coupling and fixed, thereby to secure 20 high selectivity. All these objects and others will become more apparent upon consideration of a few examples of my invention, and I now proceed to disclose a limited number of specific embodiments thereof. These 25 are shown in the accompanying drawings and the following description refers specifically thereto. It will be understood that various modifications may be made within the scope of my invention.

30 In the drawings, Figure 1 is a diagram of an embodiment of my invention involving an audion detector; and Figure 2 is a diagram showing such audion detector and circuit connections for receiving by the "beat" 35 method.

Referring particularly to Figure 1, the antenna 11 is connected through the adjustable condenser 12 and adjustable coil 13 to ground 15. At the ends of the coil 13, one 40 of which is adjustable at 14, taps are taken to the respective condensers 16 and 17, each of small capacity relatively to the condenser 12. These small condensers 16 and 17 constitute an electrostatic coupling. The opposite terminals of these condensers 16 and 17 are connected to the adjustable condenser 18 and adjustable coil 19 arranged in multiple to constitute a loop circuit. The adjustment of the coil 19 may be effected by 45 shifting the terminal 20. The circuit of the condenser 18 and coil 19 constitute a tuned secondary circuit.

The coil 21 is coupled comparatively tightly to the coil 19 and one terminal goes 50 through the condenser 22 to the grid 23 of

the audion 35, the other terminal 26 of the coil 21 going to the hot filament 24 fed by the battery 25. The plate 27 is connected through the battery 28, the condenser 29 and head telephone 30 in multiple, and the conductor 31, to the filament 24.

By means of the adjustable condenser 12 and the adjustment 14 on the coil 13, the antenna can be tuned to the frequency of the waves desired to be received. Also by 60 means of the adjustable condenser 18 and the coil 19 adjustable at 20, the loop circuit 18-19 can be tuned to the same frequency. Through the tightly coupled transformer 19-21 the oscillations of this frequency are 65 communicated with a high degree of selectivity to the audion 35.

The electrostatic coupling constituted by the small condensers 16 and 17 is very effective to render the system highly selective 70 with respect to persistent oscillations. That is, it makes the system highly selective to any particular sustained frequency. This idea is involved in my Patent No. 1123098 granted December 29, 1914. With respect to 75 disturbances of an impulsive nature, such as highly damped waves or static effects, the electrostatic coupling 16 and 17 in itself may not exclude such impulsive disturbances, and the addition of the electromagnetic coupling 80 19-21 gives the advantage that it renders the system immune with respect to all electrical disturbances whether persistent oscillations of undesired frequency or of impulsive type. It is an advantage of practical 85 operation that the coupling 19-21 can be fixed for a considerable range of wave lengths so that no adjustment thereof is required.

For the reception of undamped waves by 90 the "beat" method, I arrange the apparatus as shown in Figure 2, which is substantially the same as Figure 1, except that the conductor 31 is interrupted and its two parts 31' and 31'' include between them the coil 10 32 which is placed in inductive relation with the coil 19. Thus the circuit 18-19 not only has the oscillations of received wave frequency impressed from the antenna, but also oscillates with a slightly different frequency 10 determined by its own constants. These currents of two slightly differing frequencies combine and produce a beat effect, this effect being transmitted through the coupling 19-21 to the audion.

I claim:

In a radio receiving system, an antenna, a coil connected through a variable condenser to the antenna, leads extending from the antenna connection and the coil, said last mentioned lead having variable contact with the coil, a lead to ground extending from the

last mentioned lead, a loop circuit receiving energy through an electro-static coupling, a coil tightly coupled magnetically to the inductance coil of said loop circuit, and an audion detector connected across said magnetically coupled coil. ¹⁰

LOUIS COHEN.
